UNITED STATES PATENT OFFICE.

CHALMERS LARIER GLENN, OF WINSTON-SALEM, NORTH CAROLINA, ASSIGNOR TO BUCK & GLENN, INC., OF WINSTON-SALEM, NORTH CAROLINA, A CORPORATION OF NORTH CAROLINA.

DESIGN FOR A TOY BANKING-ROOM.

50,382.

Specification for Design.

Patented Feb. 27, 1917.

Application filed November 24, 1916. Serial No. 133,262. Term of patent 7 years.

To all whom it may concern:

Be it known that I, CHALMERS L. GLENN, a citizen of the United States, residing in Winston-Salem, in the county of Forsyth and State of North Carolina, have invented a new, original, and ornamental Design for a Toy Banking-Room, of which the following is a specification, reference being had to the accompanying drawing, forming part thereof.

The figure is a side elevation of a toy banking room, showing my new design.

I claim:

The ornamental design for a toy banking room, as shown.

CHALMERS LARIER GLENN.
